DISPLAY PACKAGE FOR A DOLL OR THE LIKE

Albert B. Rose, Brooklyn, N.Y., assignor to Active Doll Corp., Brooklyn, N.Y., a corporation of New York

Filed July 24, 1963, Ser. No. 75,947

Term of patent 7 years

(Cl. D58—12)

FIG. 1 is a perspective view of a display package for a doll or the like, showing my new design.

FIG. 2 is a top view thereof.

FIG. 3 is a side view thereof.

FIG. 4 is a rear view thereof.

The bottom view is plain.

I claim:

The ornamental design for a display package for a doll or the like, substantially as shown and described.
